UNITED STATES PATENT OFFICE.

CHARLES A. BERNHARD, OF CHICAGO, ILLINOIS.

METALLIC KITCHEN-CABINET.

1,296,908.

Specification of Letters Patent. Patented Mar. 11, 1919.

Application filed July 26, 1918. Serial No. 246,854.

To all whom it may concern:

Be it known that I, CHARLES A. BERNHARD, a citizen of the United States, and a resident of the city of Chicago, in the county 5 of Cook and State of Illinois, have invented a certain new and useful Improvement in Metallic Kitchen-Cabinets; and I do hereby declare that the following description of my said invention, taken in connection with the 10 accompanying sheet of drawing, forms a full, clear, and exact specification, which will enable others skilled in the art to which it appertains to make and use the same.

My invention relates generally to improvements in metallic kitchen cabinets; and it consists, essentially, in the novel and peculiar combination of parts and details of construction, as hereinafter first fully set forth and described and then pointed out in 20 the claims.

The object of this invention is the production of an efficient and highly sanitary kitchen cabinet, which is made entirely of sheet metal, and, therefore, absolutely ver- 25 min-proof.

To attain these objects, and others which will hereinafter appear, I construct this article of furniture, in the preferred embodiment of my invention, as illustrated in the 30 drawings forming a part of this specification, and in which Figure 1 is a perspective view of this kitchen cabinet. Fig. 2 is a vertical transverse section of the same. Fig. 3 is a detail of a fragment of the cabinet, 35 showing the means for supporting the door of the cabinet in turned-down position; and Fig. 4 is a similar view illustrating the door in closed condition. Fig. 5 is a detail edge-view illustrating the horizontal bars on 40 which the drawers are constructed to slide. Fig. 6 is a sectional view of one of the cross bars and an elevation of one of the horizontal bars associated therewith. Fig. 7 is a plan of one of the drawers; and Fig. 8 is a 45 sectional view thereof on line 8-8 of Fig. 7.

Like parts are designated by the same characters and symbols of reference in all the figures.

This cabinet comprises a rear wall 12, two 50 side walls 13, a top wall 14, and a bottom 15. The rear, and the two side walls are, preferably, formed of one sheet of metal, such as tin-plate, galvanized iron, or black sheet-steel, by being bent longitudinally, in 55 a well-known manner; or they may be separately formed and secured together in any

approved manner. The two side walls are at their forward longitudinal margins bent at right angles, as at 16, and then doubled upon themselves, as at 17, Fig. 5, thereby 60 forming reinforced margins for these bent portions, and leaving the front of the structure open, the opening extending from the top 14 to the bottom 15; and in this opening there are a series of cross bars 18, 18^a, while 65 on the inner surfaces of the side walls 13, there are placed opposing horizontal bars 19, 19^a, 19^b, which latter bars afford ledges upon which drawers, hereinafter to be referred to, are located, and these ledges have 70 shoulders, or offsets 50, between which these drawers are guided. These bars are made from sheet metal bent to approximately U-shape transversely, as best seen in Fig. 5, and they are provided with laterally-extending 75 flanges 21, by which, and, preferably rivets, 22, these bars are securely fastened to the side walls of the structure. The top wall 14 is somewhat below the upper margins of the rear, and side walls, and there is 80 placed upon these upper margins a board A, which board is admirably adapted to serve as a bread-board. Below, this bread-board A has cleats 23, which retain the bread board 85 removably in position.

Upon the upper bars 19 there is slidably placed a drawer B, having medially a partition 24, to divide this drawer into two compartments; and on its front wall 26, it is provided with a suitable drawer-pull 25. 90 Upon the bars 19^a, located below the bars 19, there is slidably located a comparatively deep drawer C, which is especially designed for use as a flour bin. This drawer C has a front wall 26^a, and side walls 27, while its 95 bottom 28, which extends from the upper margin of the front wall to the rear upper edges of the side walls, is approximately semi-circular, and it has at the rear an inwardly extending ledge 29. The object of 100 this ledge is primarily to prevent flour dumped into the bin from the usual flour-sacks or bags, from flying over the back of the bin, and, secondarily, to reinforce the end of the drawer, its forward edge being stiffened by being "wired" in the well-known manner, as illustrated at 30. At the lower margins of the front wall 26^a of this bin there is an angle bar 31, which reinforces this front wall; and at the rear of the side 110 walls of this bin there is a similar angle bar 32, connecting the longitudinal lower mar-

gins of the side walls, there being no rear wall in this drawer C. These two angle bars 31, 32, have one of their limbs horizontally disposed; and these limbs slide upon the 5 ledges of the cross bars 19^a, to afford ample bearing surfaces for this drawer C.

Below the horizontal bars 19^a there are angles or other suitable supports 33, upon which is removably located a shelf or rack 10 D; and below this shelf, and sliding upon longitudinal bars 19^b, there is a drawer E, which when pushed entirely within the structure, has its front wall 34 flush with, or slightly beyond, the face of the structure. 15 At this face, and crossing the same, there is secured a bar 18^a, having hinge-members 35, to which is hingedly connected a door F, by hinge-knuckles 36, formed at the lower edge of said door, said door reaching to near the 20 lower margin of the front wall of the drawer C. This door has a door-knob or button 37, by which it may be locked. It is constructed to swing downwardly to substantially horizontal position, as illustrated in Figs. 2 and 25 3, and in this position it is supported by pulling a drawer G, about halfway out of the cabinet. This door affords a shelf, table, or platform upon which articles may be placed prior to placing them into the proper 30 drawer, or when removing them therefrom. And in order to support this drawer in horizontal position without the aid of the drawer G, there are placed, approximately medially of the door and at its vertical margins, loops 35 or cleats 38, in each of which there is pivotally mounted a brace-rod 39, the said rod passing through an opening 40, in the front of the structure to the interior thereof; said rod having at its inner end a hook 41, which 40 bears against the inner surface of the marginal front and thereby prevents the brace-rod 39 from being pulled out through the opening 40, and thus serve to support the door in horizontal position.

45 The location of the loops or cleats 38 on the door F is such, relative to the openings 40, that when the door is in vertical position, these two elements are in register and the rods 39 in horizontal position extending 50 into the cabinet.

It will be noted that there are in this cabinet, preferably four drawers, one of which serves as a flour bin, the upper one being designed to contain bread and other bakery 55 products, while the remaining drawers as well as the shelf D, take care of all of the matter which is usually placed into a kitchen cabinet, the door F, heretofore described being placed between the second and 60 the fourth drawer.

In order to strengthen the drawers, which as far as details of construction is concerned, are all alike, except that they are of different depths, there is located at the upper front 65 margin of each drawer a sheet metal bar 43,

best seen in Figs. 7 and 8, which bar is approximately V-shaped in transverse section, and securely fastened to the front wall in the following manner:

The horizontal portion 44 of this bar 43 70 has an upwardly-extending flange 45; and the upper margin of the front 26^b is doubled upon itself as at 47, with the flange 45 therebetween, which securely holds the V-shaped bar in position, the doubling-up of the upper margin of the drawer-front also reinforcing the same; and it may here be stated that this front has its remaining three margins, and the forward edges of the sides of the drawer, edged and locked in the same 75 manner, so that there are three thicknesses of metal at these margins. This construction of the drawers is shown as applied to drawer G in Figs. 7 and 8; but as already stated the same construction is employed in 80 drawers B, C, and E.

The end walls of the drawers are preferably lock-seamed to the side walls thereof, as illustrated at 49 in Figs. 7 and 8, which provides for a very substantial construction 90 without the use of solder or other means of fastening the bottoms or ends of the drawers to the side walls thereof; and to further strengthening the construction, the upper margins of the side, and end, walls are inwardly turned, as shown at 42.

As hereinbefore stated, the bars 19, 19^a, 19^b, are substantially U-shaped in transverse section; but to afford guiding means for the drawers there is formed in each bar an offset 100 or shoulder 50, as shown in Figs. 5 and 6, which I find necessary owing to the fact that the width of the drawers is equal to the distance between the longitudinal margins of the right-angular portion of the side walls, 105 and that the bars 19, 19^a, 19^b, are secured to the side walls but must project a reasonable distance beyond the margins of these walls to afford the sliding surfaces for the drawers, as illustrated in Fig. 5, which, however, 110 affords no guiding means for these drawers unless these bars are provided with the shoulders 50 hereinbefore described.

It will now be further observed that the portions of the drawer-fronts which project beyond the side walls, the top, and the bottom of these drawers overlap the face of the cabinet and thus effectively close this front when the door is closed and the drawers all in normal, pushed-in position, so that 115 vermin, especially the small black ants so frequently found in kitchens, cannot enter the cabinet. To afford proper ventilation there are openings 51, in the lower portion of the side walls, and similar openings 52 in 120 the upper part of the rear wall, said openings being covered by very fine wire gauze or minutely perforated sheet metal.

The cabinet is, preferably, white-enamored on its exterior and interior surfaces; 130

but the surfaces of the drawers are, preferably, left in their natural condition; all of the said drawers being, preferably, made from the best quality of tin-plate which is 5 heavily coated with pure tin, and therefore highly sanitary.

I have hereinbefore described with considerable minuteness the preferred embodiment of my invention; but I desire it to be 10 understood that I am aware that changes may be made therein, and parts omitted without departing from the scope of my invention as defined in the appended claims.

Having thus fully described this invention, I claim as new, and desire to secure to myself by Letters Patent of the United States—

1. A kitchen cabinet of metallic construction comprising, a rear wall, two side walls, 20 a top, and a bottom, said side walls having their longitudinal outer edges bent at right angles, and the right-angled portions bent upon themselves, a series of cross bars connecting these right-angled portions, a series 25 of longitudinal bars, said longitudinal bars being secured to the inner surfaces of the side walls, said longitudinal bars being approximately U-shaped in cross section, there being on the upper members of these bars 30 offsets, said upper members being flush with the upper surfaces of the cross bars, and said offsets being flush with the marginal edges of the right-angled portions of the side walls, and a series of drawers slidably 35 mounted on said longitudinal bars at the offset portions thereof.

2. In a metallic kitchen cabinet, the combination, of a rear wall, two side walls, a top, and a bottom, said side walls having 40 their longitudinal forward edges bent at right angles, and the right-angled portions doubled upon themselves, a series of cross bars connecting these right-angled portions,

a series of longitudinal bars secured to the inner surfaces of the side walls, said longitudinal bars extending beyond the marginal right-angled portions of said side walls, a series of drawers slidably mounted upon said longitudinal bars, there being between two of said drawers a space, a door 45 50 constructed to close said space, said door being hingedly connected to one of said cross bars to swing downwardly, two suspension rods pivotally connected to said door and entering said space, there being at the inner ends of said suspension rods hooks adapted to bear against the inner surfaces of the right-angled portions of said side walls.

3. In a metallic cabinet, the combination, of a rear wall, two side walls, a top, and a bottom, said side walls having their longitudinal forward edges bent at right angles to project inwardly into the cabinet, said right-angled portions being bent upon themselves, a series of cross bars connecting these 65 right-angled portions, a series of longitudinal bars secured to the inner surfaces of the side walls, said longitudinal bars extending beyond the marginal right-angled portions of said side walls, drawers slidably 70 mounted upon said longitudinal bars, there being between two of said drawers a vacant space, a door constructed to close said vacant space, said door being hingedly connected to one of said cross bars to swing 75 downwardly, a drawer below said door which when partly pulled out will support said door in downwardly turned position, and auxiliary means pivotally connected to said door to support said door in downwardly turned position, and to swing into the cabinet when said door is being closed.

In testimony that I claim the foregoing as my invention, I have hereunto set my hand.

CHARLES A. BERNHARD.
